Primary Examiner — Wendy L Arminio(74) *Attorney, Agent, or Firm* — Nitin Kaushik(57) **CLAIM**

The ornamental design for a record player, as shown and described.

DESCRIPTION

FIG. 1 is a front, top and right side perspective view of a record player, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is an enlarged detail view of area 8 in FIG. 1;

FIG. 9 is an enlarged detail view of area 9 in FIG. 1; and,

FIG. 10 is an enlarged detail view of area 10 in FIG. 1.

The dash-dash broken lines in the drawings illustrate the portions of the record player which form no part of the claimed design. The dot-dash broken lines in FIG. 1 and encircling FIGS. 8–10 depict the boundaries of the enlarged detail views and form no part of the claimed design.
